Atty.

UNITED STATES PATENT OFFICE

ADOLF INGVALD LUND, OF OSLO, NORWAY

REISSUED

LIST OR FILLET FOR CREVICES

Application filed October 29, 1931, Serial No. 571,774, and in Norway November 1, 1930.

My invention relates to a list or fillet adapted to be used in the joints between plates which cover walls, ceilings and the like, and it is the object of the invention to 5 provide a list or fillet which is cheap to manufacture, easy to use and which will cover the joint completely but at the same time allow the plates to move a little relatively to each other.

10 A suitable material for the new list or fillet is according to the invention a fibrous material, e. g. paper, cardboard, pasteboard, millboard and the like, which although it may easily be given the desired shape will 15 be stiff and resilient enough for the present purpose.

The fillets may be manufactured half-ready for use in the form of sheets or webs, from which the single fillets may be severed 20 and bent to final shape.

The invention is illustrated, by way of example, on the accompanying drawing whereon

25 Figs. 1, 2 and 3 disclose different embodiments of the new list or fillet.

Fig. 4 illustrates in cross section the list in Fig. 1 placed between two wall cover plates.

Fig. 5 is a similar view of the list shown in Fig. 2 and

30 Fig. 6 illustrates how the lists may be manufactured in plates or webs from which the lists are later severed and bent to the final desired shape.

In Fig. 1 the list is shown in the shape of a 35 massive rail having a head portion 1 and a leg portion 2, the latter being at its free end provided with flanges 3 extending laterally.

The head portion is preferably somewhat oval in cross section, as shown. Fig. 4 illustrates how such a list may be placed between 40 two plates 4, 4. The flanges 3, 3 then will rest against the rear side of the plates, and the head portion 1 entirely covers the joint between the plates, so that no crevice is seen

45 from the outer side. The length of the portion 2 is of course chosen so as to correspond to the thickness of the plates 4. The head portions 1 will also, to a greater or lesser degree, mark the borders of the adjoining plates

50 and thus better indicate the pattern formed by the plates.

In Figs. 2 and 3 are illustrated lists or fillets prepared from sheet or web material. The head portion 1 is formed circular or

55 oblong in cross section as shown or, may

also be of angular or other shape, and from the head extend two middle portions 2' each provided with a flange 3. If such a list is placed between two plates 4 as indicated in Fig. 5 the head 1 also will cover the joint between the plates, while the flanges 3 grip behind the plates. If the plates 4 for any reason should move somewhat away from each other the portions 2' will move also, due to the resiliency of the list, and no crevice will 60 occur. This also makes the construction safer in case of fire, as no air draft occurs through the joint.

In order to make the manufacture, transportation and adaption of the lists cheap they 70 may be manufactured in the form of sheets or webs and eventually rolled into reels from which the desired lengths may be severed, and then bent to final shape as they are placed in position.

Fig. 6 illustrates a portion of such a sheet. By passing the blank between suitable rollers or the like the head portion 1 is formed and at the same time weakening lines 5 are made, along which the flanges 3 are bent later on. If two or more lists are pressed side by side 80 in a blank, weakening grooves or perforations 6 are provided, along which the several lists may be severed, e. g. by means of a pair of scissors. Then the severed list is bent 85 to a shape somewhat as illustrated in Fig. 2.

It may be of advantage to insert in the head portion a thread, cord or the like, to make it more resistant against deformation and at the same time increase the springy action 90 outwardly of the portions 2'.

I claim:

As an article of manufacture, a fillet for joints of adjoining wall-plates, made of resilient fibrous material and comprising an enlarged head portion, and a leg portion disposed substantially at right angles to said head portion and having weakening lines permitting flanges to be formed extending 100 in opposite directions at substantially right angles from said leg portion.

In testimony whereof I affix my signature.

ADOLF INGVALD LUND.
